UNITED STATES PATENT OFFICE.

SOLOMON C. BRANUM, OF OKLAHOMA CITY, OKLAHOMA, ASSIGNOR OF ONE-HALF TO
JOE E. MASON, OF OKLAHOMA CITY, OKLAHOMA.

SACK HOLDER.

Application filed October 5, 1926. Serial No. 139,680.

The object of the invention is to provide a simple and cheap device adapted particularly for the use of cotton pickers to enable the sack to be carried thereby and at the same time have the mouth or upper end held open so that the cotton may be readily deposited therein.

With this object in view, the invention consists in a construction and combination of parts of which a preferred embodiment is illustrated in the accompanying drawings, wherein:

Figure 1 is a perspective view showing the invention applied in operative position.

Figure 2 is a perspective view of the device per se.

The holder is preferably made of a single strand of spring steel wire bent at an intermediate point to provide a crotch 10 of which the legs 11 are of arcuate form and arranged in divergent relation, the strand being bent downwardly at the ends of the legs 11, as indicated at 12, and then again bent to provide the two lateral arms 14 which are of arcuate form and extend in opposite directions from the crotch, terminating in inturned portions 15 from which extend the vertical leg portions 16 which are terminated in horizontally arranged loops 17. The downwardly turned portions 12 adjacent the lateral arms 14 are spanned by a plate 18, coiled around them as indicated at 19, this plate bracing the holder in the region of the crotch 10.

In use, the device is inserted in the open end of the sack and the upper edge brought

up to the plane of the loops 17, the edge portion at one point being forced down into the crotch 10, and at other points being folded over the loops 17 as shown in Figure 40. The strap 20 for supporting the sack on the shoulder of the operator is threaded into the loops 17 from which it may be readily disengaged when the sack is filled and the spreader or opener withdrawn therefrom. 45

The invention having been described, what is claimed as new and useful is:

1. A device for the purpose indicated having a vertically arranged section defining a crotch, arms extending from said section and terminating in upstanding leg portions having horizontally arranged loops at their upper ends. 50

2. A device for the purpose indicated having a vertically arranged section defining a crotch, arms extending from said section and terminating in upstanding leg portions having horizontally arranged loops at their upper ends, the loops being arranged in a plane parallel with the plane of the arms. 55

3. A device for the purpose indicated having a vertically arranged section defining a crotch, arms extending from said section and terminating in upstanding leg portions having horizontally arranged loops at their upper ends, the loops being arranged in a plane parallel with the plane of the arms and the latter being of arcuate form. 60 65

In testimony whereof he affixes his signature.

SOLOMON C. BRANUM.
